UNITED STATES PATENT OFFICE

111,058

DESIGN FOR A COMBINED DESK AND SEAT

Carl T. Anderson, Madison, Wis.

Application May 27, 1938, Serial No. 77,434

Term of patent 14 years

To all whom it may concern:

Be it known that I, Carl T. Anderson, a citizen of the United States, residing at Madison, in the county of Dane and State of Wisconsin, have invented a new, original, and ornamental Design for a Combined Desk and Seat, of which the following is a specification, reference being had to the accompanying drawing, forming a part thereof.

In the drawing,

Fig. 1 is a view in perspective of a combined desk and seat showing my new design.

Fig. 2 is a side view thereof.

I claim:

The ornamental design for a combined desk and seat, substantially as shown.

CARL T. ANDERSON.
